JOHN K. CARTER, OF CLARKSVILLE, ARKANSAS

MEASURING DEVICE

Application filed November 22, 1928. Serial No. 321,219.

This invention relates to a gasoline dispensing apparatus.

An object of the invention is the provision of a dispensing device which will positively determine the quantity of gasoline dispensed by a weighted element that controls the operation of a reciprocating tank containing the gasoline, said tank co-operating with an outlet pipe for closing or opening said pipe to permit the discharge of gasoline from the reciprocating tank or chamber.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a view in perspective of a device constructed in accordance with the principles of my invention,

Figure 2 is a fragmentary vertical section of the apparatus,

Figure 3 is a horizontal section taken along the line 3—3 of Figure 2,

Figure 4 is a horizontal section taken along the line 4—4 of Figure 2.

Referring more particularly to the drawings 10 designates a pumping stand of standard construction having a crank 11 attached to the usual mechanism (not shown) for operating the pump and forcing the gasoline into a container 12. The upper end of the stand is provided with a screen 13 to protect the glass casing 14 supported in a flange 15 at the upper end of the stand and having a cap closure 16.

The container 12 is formed of any suitable material and has a depending arm 20 pivotally connected at 21 with a lever 22 fulcrumed, at 23, on a strap or hanger 24 depending from the top 25 of the stand 10. The lever 22 is provided with notches 26 adapted

50 to receive a link 27 carrying a weight 28. The arm is inserted through a passage 29 of the standard 10.

An overflow pipe 30 rises through the stand 10 and terminates at 31 in a pipe 32 and is telescoped at its lower end within the pipe 30 and has its upper end, as shown at 33, in communication with the container 12 and secured to said container. A filling pipe 34 is connected with a pump (not shown) and is adapted to supply gasoline to the container 12 through a spout 35 which projects downwardly into the upper end of the container 12.

A pipe 36 is held rigidly, at 37, to a cover 16 and has its free end 38 normally engaging a bumper or seat 39 which is formed of cork and which will prevent fluid from flowing from the tank 12 through the pipe 36 and the discharge tubing 40 when the container 12 is in a position shown in Figure 2. The tubing 40 has a spout 41 controlled by a valve 42 for a purpose which will presently be explained.

The operation of my device is as follows: The crank 11 is operated until the container 12 is filled to overflow whence any excess will be drained through the pipe 32. The position of the inlet 33 of the pipe 32 is such that approximately ten gallons of gasoline may be filled into the container 12.

The weight 28 is carried by the outer end of the lever 22 in order to maintain the tank 12 in its uppermost position. If a customer desires to buy five gallons of gasoline, the weight is moved over to the point where the link 27 will rest within the notch adjacent the numeral 5. In starting the device it is necessary to prime the tube 40 and the tube 36 in any approved manner so that the tubing and pipe will be maintained full of gasoline. After the weight 28 has been set and the gasoline has been pumped into the tank or container 12, the weight of the container together with the gasoline will cause the container to be lowered by gravity, thereby removing the cork 39 away from the free end 38 of the pipe 36. As soon as the gasoline has been discharged sufficiently from the tank 12 so that the quantity remaining in the tank will counterbalance the weight

21, the container will have been moved upwardly sufficiently to cause the member 39 to engage the free end of the pipe 36 and thus cut off the flow of gasoline from the tank. It will be necessary for the operator at this time to close the valve 42 to prevent the priming charge of gasoline in the tube 40 and the pipe 36 from being released.

I claim:

10 1. A dispensing device for gasoline comprising a tank mounted for vertical reciprocation, a discharge pipe having the free end located within the container, means in the container for engaging the free end of the 15 pipe for closing the same, means for supporting the container, a weight co-operating with said supporting means for maintaining the container in an uppermost position when the container is full of liquid, and means for 20 supplying the container with liquid.

2. A gasoline dispensing device comprising a container, a discharge pipe projecting into the container, means adapted to be carried by the container and adapted to engage 25 the free end of the pipe for closing the same, said pipe acting to siphon a liquid from the container, a lever pivotally mounted intermediate its ends and having one end connected with the container for supporting said 30 container in an elevated position, a weight movably supported on the other end of the lever for counterbalancing the weight of the container and a quantity of liquid carried by the container, and means for supplying a 35 liquid to the container.

JOHN K. CARTER.
